United States Patent

Des. 239,544

Patented Apr. 13, 1976

239,544

ANIMAL SCULPTURE

Isom J. Henry, 921 S. Lyon St.,
Santa Ana, Calif. 92705

Filed Apr. 22, 1974, Ser. No. 462,956

Term of patent 14 years

Int. Cl. D11—02

U.S. Cl. D29—23 B

FIG. 1

FIG. 2

FIG. 3

FIG. 4

FIG. 1 is a perspective view of an animal sculpture showing my new design;

FIG. 2 is a bottom plan view, the base being removed for clarity;

FIG. 3 is a rear perspective view; and

FIG. 4 is a top plan view thereof.

I claim:

The ornamental design for an animal sculpture, as shown and described.
